UNITED STATES PATENT OFFICE.

JOHN R. L. SANTOS, OF BALTIMORE, MARYLAND, ASSIGNOR, BY MESNE ASSIGNMENTS, TO CHICAGO PNEUMATIC TOOL COMPANY, OF NEW YORK, N. Y., A CORPORATION OF NEW JERSEY.

PNEUMATIC TOOL.

Application filed December 15, 1922. Serial No. 607,183

This invention relates to improvements in pneumatically operated tools and in its present form has features that especially adapt it for use in a tool known as a jam-riveter.

- 5 An object of the invention is to provide an improved tool wherein the motive fluid utilized for operating the piston or plunger is controlled by a valve that is moved in both directions by live pressure.
- 10 Another object is to provide an improved tool structure in which the valve which controls the motive fluid that actuates the plunger or piston may be moved in one direction by a constant live pressure and be moved in a reverse direction by a continuous but variable live pressure.
- 15 A still further object of the invention is to provide an improved tool that embodies especially desirable features when the tool is to be used as a so-called jam-riveter.

The present invention embodies the novel features forming the subject of a companion application Serial No. 607,184, filed Dec. 15, 1922 for patent for a percussive tool which 25 application I am executing simultaneously herewith but the present application discloses a structure which is an enlargement on the device of my said companion application.

With these and other objects in view, the 30 invention is illustrated in the accompanying drawings, wherein,—

Fig. 1 shows the improved tool in vertical longitudinal section.

Fig. 2 illustrates the locking means between 35 the lower cylinder member and the cap.

Fig. 3 shows a cross-sectional detail through the tool,—the section being taken on the line 3—3 of Fig. 1.

Fig. 4 illustrates the detached valve on an 40 enlarged scale.

Fig. 5 shows in a diagrammatic way and on an enlarged scale some of the ports and passages utilized in the tool, for illustrative purposes only, and

45 Fig. 6 illustrates a similar view with the parts in a reverse position, also for illustrative purposes only.

Referring to the drawings, the numeral 1, 50 designates a plunger or piston, 2, a lower cylinder-member, 3, an upper cylinder-member, which two cylinder-members are separated by an interposed valve-box or bushing 4, in which a valve 5 is retained so as to have longitudinal movement in the box or bushing

between the two cylinder-members as and for 55 a purpose that will presently be explained.

The two cylinder-members and the valve-box are all held in rigid relation with respect to each other by means of a cylindrical cap 6 which latter telescopically fits down over the 60 upper member 3, the box 4 and has a screw-threaded engagement with the upper end of the cylinder-member 2. The cap 6 therefore is rigidly attached to the lower cylinder-member and contains the upper member and 65 the valve-box.

The lower cylinder-member 2 carries the working tool 7 at its extreme lower end and under the piston 1, where the latter may strike 70 the inner end of the tool on each of its forward strokes.

A tubular casing 8 telescopically receives the cylindrical cap and its contained parts and also encircles the lower cylinder-member 2.

This casing is, in the present instance, closed at its upper end by means of a disk 75 or plate 9.

To effectually lock the cylindrical cap 6 and the lower cylinder-member 2 against independent rotation or separation in the tubular casing, I provide a split locking ring 10, as shown in Fig. 2 of the drawing, whose ends engage notches on the cap and member 2 and thereby prevent rotation of the one 85 with respect to the other.

The tubular casing 8 has an interior shape at its lower end which coacts with the externally reduced lower end of the cylinder-member 2 so as to form a lower annular exhaust 90 chamber 12, while ports 11, one of which is shown in Fig. 1, are provided in the casing wall to serve as exhausts from said chamber 12 to the atmosphere.

The upper end of the tubular casing 8 is 95 provided with an air-supply port 13 while a passage 14 leads downwardly from said port and communicates with an annular chamber 16 which is formed between the exterior of the cap 6 and the interior of the casing 8. 100 The two chambers 12 and 16 are clearly cut off from each other by the enlargement in the lower cylinder-member 2 and the cup-leather or packing 32, thereat.

A passage 15 extends from the supply port 13 and opens into the upper casing chamber 33 above the top of the cap 6 for a purpose 105 that will presently be explained.

The upper end of the cap 6 is provided with a circumferential cup-leather or packing 31 whereby to prevent leakage of air from the upper side of the cap 6 down into the annular chamber 16.

From the foregoing explanation it will be seen that the casing 8 for all practical purposes has the form and the operation of a cylinder, while all the parts including the cylinder members 2, 3; the valve-box 4 and the cap 6 being rigidly connected, have the form and operation of a plunger.

Obviously, if fluid pressure be admitted through passage 15 into the casing-chamber 33, that pressure will act upon the top of cap 6 and push the latter down in the casing and by so doing will project the lower end of cylinder-member 2 more or less from the end of the casing.

20 The cylindrical wall of the cap 6 is provided with a plurality of ports 17 which establish communication between the annular chamber 16 on the outer side of the cap and an annular channel 19, on the inner side of said cap, which latter channel is partly around the bushing or valve-box 4 and partly around the upper cylinder-member 3.

An annular groove 18 is provided interiorly of the upper cylinder-member 3, which groove 30 is in constant communication with the annular channel 19 and the ports 17. This annular groove 18, is so positioned that it may be controlled by the valve 5 and at times exposed to the interior of the cylinder-members 3 and 5 and valve so as to admit pressure into the latter as and for a purpose that will presently be explained.

40 A vertical channel 20 extends longitudinally in the lower cylinder-member 2 and also in the valve-box 4, and the lower end of this channel opens inwardly through the wall of the lower cylinder member 2 and communicates with the lower cylinder-chamber 21, beneath the piston or plunger 1, when the latter is up. The upper end of this vertical channel 20 communicates with an annular channel 22 that is formed around the interior of the valve-box 4 two walls of which channel are produced by an overhanging shoulder 23 and 50 an annular portion 25 of the movable valve. It is therefore to be understood that the upper end of channel 20 opens under the valve shoulder 23 at which point the valve has the greatest diameter as clearly shown in Fig. 4 of the drawing.

55 By reference to Fig. 1 of the drawing it will be noted that a small port 36, extends through the valve-box 4 from the annular channel 19 to the upper end of the vertical channel 20 and as this small port is always in communication with the channel 19, ports 17 and annular chamber 16, a small jet of air under pressure will constantly be supplied to said channel 20 which will build up a pressure therein when the piston 1 closes the lower

end of the channel 20, but that said constantly-supplied air will escape from channel 20 into the lower cylinder-chamber 21 and pass out through ports 30 when the piston is up sufficiently to uncover said channel-end 20.

70 By again referring to Fig. 4, it will be noted that the upper end of the valve 5 is provided with an annular shoulder 24 which is of a lesser diameter than the annular shoulder 23, and by reference to Figs. 1-5 and 6 of the drawings it will be seen that this upper shoulder 24 of the valve is positioned so that it may be constantly exposed to the pressure fluid admitted from the chamber 16 through the groove 18.

80 The lower end of the valve has an annular portion 26 of the same diameter as the annular portion 25, and between said two annular portions said valve has an annular groove 27 which serves a useful purpose as will presently be explained.

85 A lift-channel 28, extends longitudinally in the wall of the lower cylinder-member 2 and also up into the valve-box 4 and the upper end of this lift-channel connects with a valve-box port 29 which latter registers with the annular groove 27 of the valve. The lower end of lift-channel 28, terminates in the chamber 21 of cylinder-member 2 adjacent to the working tool 7 and beneath the piston 1 as clearly shown in Figs. 1 and 6 of the drawings.

90 Ports 30 are provided in the lower cylinder-member which connect the cylinder-chamber 21 with the annular exhaust-chamber 12 so that pressure under the piston and from channel 20 may escape to the atmosphere when the piston is up.

95 It is to be noted that the upper cylinder-member 3, the valve 5 and the upper end of the cylinder-member 2 are all open centrally and form an upper piston-chamber 35 so that the piston may travel through the valve from one cylinder member to the other. The cap 6 extends over and forms the upper end of the upper cylinder chamber.

100 Longitudinal cylinder passages 37 are provided which have the lower ends in constant communication with the exhaust by way of ports 30 (see the diagrammatic view of Fig. 6) and the upper ends of these passages connect with ports 38 in the valve-box 4, so that said valve-box ports are always open to the exhaust by way of ports 30, annular chamber 12 and port 11.

105 In the valve-box there are passages 41 which extend from upper valve-box ports 42, down to and connect with the upper ends of the cylinder passages 37 and as the box-ports 42, open at the upper side of the large upper valve shoulder 44, these ports and passages 41 and 37 provide a constant relief to vent pressure from valve shoulder 44 to the atmosphere.

110 The valve-box 4 is provided with a port 130

40 which opens at the side of the valve and a port 39, extends from this port 40 up through the box and into the lower part of upper cylinder-element 3 where it communicates with the annular groove 18, which latter is constantly supplied or charged with live fluid pressure.

The annular channel 22 around the interior of the valve-box 4 is supplied with fluid pressure by a passage 43 from annular chamber 19.

Operation.

Presuming a suitable throttle valve to be 15 screwed into the supply port nipple 13 and that said throttle is designed to control the admission of fluid pressure to passages 15 and 14.

Fluid pressure entering chamber 33 20 through passage 15 will act on the end of cap 6 which serves as a plunger-head. At this moment the tool will be in place against the work and may be sustained or braced at the casing end 9 so that movement of the entire 25 tool in a rear direction may be prevented.

As pressure is admitted into chamber 33 that pressure will act upon the head-end of cap 6 and move the same forward in the casing 8. This forward movement of the cap in 30 the casing will cause a like movement of the two cylinder-members 2 and 3 and the interposed valve-box 4,—the forward end of cylinder-member 2, thus being projected from the casing until the working tool 7 seats 35 against the work to be acted upon. This forward-acting pressure in chamber 33 is maintained to keep the cylinder-members pressed forward and also to advance the same as the work progresses.

40 The fluid-pressure admitted through passage 14 will pass into annular chamber 16, between the casing and cap, then through ports 17 into annular chamber 19 and annular groove 18 around the interior of the upper cylinder-chamber 35.

Presuming valve 5 to be down in the valve-box 4, and piston 1 to be down in the lower cylinder-chamber 21.

When valve 5 is down its upper end will 50 uncover the annular groove 18 around the upper cylinder-member 3 and thereby permit fluid pressure from said groove to pass down over the top of the valve and through the central passage thereof to the upper side 55 of the piston 1 which latter will be driven down. At this time, as piston 1 approaches the end of its forward stroke it will cover the lower end of channel 20 so that the fluid pressure entering the upper end of this channel 60 20 by port 36, will build up a pressure in annular groove 22 beneath the large shoulder 23 of the valve and lift the latter, even against the pressure on the smaller shoulder 24 of the valve, thereby cutting off the supply 65 of fluid pressure into upper chamber 35 and

at the same time uncovering valve-box port 38, so as to permit the pressure on the upper side of piston 1 to vent from chamber 35 and pass out through passages 37 and ports 30 into the annular exhaust-chamber 12 from 70 which it will exhaust to the atmosphere through casing port 11.

When the pressure above the piston is thus relieved and the valve is up, the annular channel 27 of the valve forms a connection between port 40 and port 29 so that live air from the constant supply in annular channel 18, around the upper end of the valve, will pass down passage 39 to port 40; then into annular valve-groove 27; then out through 80 port 29 to and down through channel 28 to the lower end of lower cylinder-member 2 into chamber 21 beneath the piston 1 where it may act upon the piston and drive the latter up.

As the piston moves up its bottom or lower end will uncover the entrance from chamber 21 to channel 20 so that the fluid pressure (air) can escape from said channel into the cylinder and from the latter by the ports 30 90 to the annular chamber 12 and thence to the atmospheric by exhaust port 11.

This venting from channel 20, reduces the pressure from beneath the shoulder 23 of the valve so that the pressure on the valve-shoulder 24 (which is constant) can move the valve down as the piston nears the upper end of its stroke and thereby admit pressure on top of the piston for driving the piston down again.

100 Annular channel 27 in the valve makes a connection between ports 29 and 38 of the valve-box and thereby exhausts air from beneath the piston by passages 28, passage 38 to port 30 and thence to atmosphere.

The port 43 in the valve-box is uncovered by the valve when the latter is in the up position and at this time admits air from annular chamber 19 to channel 22 so as to augment the pressure from port 36 to act on the valve 110 shoulder 23 and thereby keep the valve up the desired length of time after the bottom of the piston has uncovered ports 20 and 30.

Having described my invention, what I claim is—

115 1. In a percussive tool, a cylinder, a plunger, a valve to control the admission of motive fluid to opposite sides of the plunger said valve having an area subject to a substantially constant pressure and a larger opposed area subject to a continuous variable pressure, a casing around the cylinder and forming an annular pressure supply chamber around one portion of the cylinder and said casing forming an annular exhaust chamber around another portion of the cylinder, exhaust connections to and from said latter chamber, supply connections to the first-named chamber, and means for moving the cylinder longitudinally of the casing.

2. In a percussive tool, a cylinder having an imperforate rear end, a piston reciprocable within said cylinder, a casing around the closed end of said cylinder and cooperating with said cylinder to form an annular pressure supply chamber, means establishing communication between said supply chamber and the interior of said cylinder for effecting reciprocation of said piston, and means for moving said cylinder longitudinally in said casing while maintaining said connection.

3. In a percussive tool, a cylinder, a closure for said cylinder having an imperforate end, a piston reciprocable within said cylinder, an automatic distributing valve for con-

trolling the admission of motive fluid to opposite sides of said piston to effect movement of the latter, a casing around said cylinder and enclosing said closure end, said casing 20 cooperating with said cylinder and closure to provide spaced annular chambers around said cylinder, one of said annular chambers being continuously open to exhaust, means for conducting motive fluid to said other annular 25 chamber, means for moving said cylinder within said casing said casing having ports and passages communicating with said annular chambers in all positions of said cylinder within said casing.

In testimony whereof I affix my signature.

JOHN R. L. SANTOS.
